CIGARETTE LIGHTER

Emile Gilberton, Paris, France, assignor to Etablissements Genoud & Cie, Venissieux-Rhone, France

Filed Mar. 29, 1962, Ser. No. 69,496

Term of patent 7 years

(Cl. D48—27)

FIGURE 1 is a side elevational view of a cigarette lighter showing my new design, the opposite side being substantially the same,

The characteristic features of my design for the lighter disclosed reside in the cap and handle members as best shown in FIGURES 1 and 4.

I claim:

The ornamental design for a cigarette lighter, as shown and described.
